CLAIM

The ornamental design for a tablet computer dock, as shown and described.

DESCRIPTION

FIG. 1 is an isometric view of a tablet computer dock showing our new design.

FIG. 2 is a top plan view of the tablet computer dock shown in FIG. 1.

FIG. 3 is a front elevation view of the tablet computer dock shown in FIG. 1.

FIG. 4 is a left side elevation view of the tablet computer dock shown in FIG. 1.

FIG. 5 is a right side elevation view of the tablet computer dock shown in FIG. 1.

FIG. 6 is a rear elevation view of the tablet computer dock shown in FIG. 1; and,

FIG. 7 is a bottom plan view of the tablet computer dock shown in FIG. 1.

The broken lines in FIG. 7 depicts portions of the tablet computer dock that form no part of the claim.
